Primary Examiner—Freda S. Nunn*Assistant Examiner*—Kevin K. Rudzinski(74) *Attorney, Agent, or Firm*—Michael Best & Friedrich LLP(57) **CLAIM**

The ornamental design for a fan light cover, as shown and described.

DESCRIPTION

FIG. 1 is a perspective view of a fan light cover constructed in accordance with an embodiment of the present invention; FIG. 2 is a top view of the fan light cover shown in FIG. 1; FIG. 3 is a front view of the fan light cover shown in FIGS. 1 and 2; and,

FIG. 4 is a side view of the fan light cover shown in FIGS. 1-3.

The broken line showing of the connection between the front and rear is for illustrative purposes only and forms no part of the claimed design.
